(57) CLAIM

The ornamental design of a football, as shown and described.

DESCRIPTION

FIG. 1 is a perspective view showing my new football;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The stripe area of the design is lined for color. The broken lines surrounding the lacing and on the lower left side of the football are for illustrative purposes only and form no part of the claimed design.
